HEM AID AND BUTTONHOLE GUIDE

Ann R. Bozzi, Franklin Square, N.Y., assignor to David Traum, Inc., New York, N.Y., a corporation of New York

Filed June 7, 1968, Ser. No. 12,254

Term of patent 14 years

Int. Cl. D15—09

U.S. Cl. D52—6

FIG.1

FIG.3

FIG. 1 is a top plan view of the hem aid and buttonhole guide, showing my new design;

FIG. 2 is an edge or front elevational view of the same; and

FIG. 3 is a bottom plan view of the same.

I claim:

The ornamental design for a hem aid and buttonhole guide, substantially as shown.
